United States Patent [19]
Stuhlmacher

[11] Patent Number: Des. 317,776
[45] Date of Patent: ** Jun. 25, 1991

[54] ELECTRICAL ROCKER SWITCH
ACTUATOR ASSEMBLY

[75] Inventor: John Stuhlmacher, Crown Point, Ind.

[73] Assignee: McGill Manufacturing Company,
Inc., Valparaiso, Ind.

[**] Term: 14 Years

[21] Appl. No.: 421,389

[22] Filed: Oct. 13, 1989

[52] U.S. Cl. D13/174; D13/169

[58] Field of Search 200/315, 339, 302.3;
D13/158, 169, 173, 174

[57] CLAIM

The ornamental design for an electrical rocker switch actuator assembly, as shown and described.

DESCRIPTION

FIG. 1 is a perspective view of an electrical rocker switch actuator assembly showing my new design;

FIG. 2 is a top plan view thereof;

FIG. 3 is a front elevational view thereof, the rear elevational view thereof being a mirror image;

FIG. 4 is a right side elevational view thereof;

FIG. 5 is a left side elevational view thereof;

FIG. 6 is a bottom plan view thereof.

The surface shading in FIGS. 1, 2, 3, 4 and 6 indicates contrast as well as contour.

FIG. 1

FIG. 2

FIG. 3

FIG. 4

FIG. 5

FIG. 6
